FIRE LADDER

Morris Honig, New York, N. Y.

Application April 22, 1932. Serial No. 606,794

4 Claims. (Cl. 227—12)

This invention relates to new and useful improvements in a safety elevator.

This invention is similar in subject matter to my Patent No. 1,794,175, issued February 24, 5 1931.

The invention has for an object the construction of a safety elevator which is characterized by a plurality of substantially U shaped members set into each other and formed at the sides with 10 guide arms extended into each other, and a carriage riding upon said guide arms.

Furthermore, the invention proposes the arrangement of means for extending the various U shaped members so that different heights may 15 be reached.

As another object of this invention it is proposed to provide means whereby the various U shaped members may be held at different inclinations.

20 The invention has for a still further object the construction of a device of the class mentioned which is of simple durable construction and which may be manufactured and sold at a reasonable cost.

25 For further comprehension of the invention, and of the objects and advantages thereof, reference will be had to the following description and accompanying drawing, and to the appended claims in which the various novel features of the 30 invention are more particularly set forth.

Figure 1 is a side elevational view of a device constructed according to this invention.

Figure 2 shows the same device applied upon 35 a truck.

Figure 3 is a front elevational view of the device shown with the U shaped arms in the vertical position.

Figure 4 is a sectional view and under line 4—4 of Figure 3.

40 Figure 5 is a fragmentary enlarged elevational view looking in the direction of the line 5—5 on Figure 4.

Figure 6 is a fragmentary side elevational view 45 of the carriage showing the rollers in detail.

In Figure 1 the safety elevator is shown disposed within a cavity formed to the front of a building 11. A removable cover, 12, closes the cavity.

The safety elevator consists of a plurality of substantially U shaped members 13, one set 50 into the other. Upon the arms of each of the U shaped members there are formed guides 14 which are also set into each other so that the U shaped members may be extended in telescopic fashion.

A means is provided for holding the various U 55 shaped members in different inclined positions.

This means consists of a shaft 15, rotatively supported on standards 16 mounted in the cavity 10. The innermost of the U shaped members 13, is rigidly secured at the bottom end 17 upon the shaft 15. A gear 18 is fixed upon the shaft 15, 60 and meshes with a train of gears 19, terminating in a worm 20. The worm 20 is fixed upon a vertical shaft 21, which has a head formed at the upper end and located within a recess 22 in the ground so that the elevator may be raised to 65 various inclined positions by placing a turning tool upon the head. Dot and dash lines 24 illustrate the elevator resting against the building 11 in various inclined and extended positions.

A carriage is disposed between the arms of the 70 U shaped members and at the sides provided with a roller structure engaging the guides 14. Each of these roller structures consists of a bracket 27 upon which a pair of arms 28 are swivelly mounted. Rollers 29 are mounted upon the outer end of 75 the arms 28. Springs 30 are coaxially mounted upon the pivots of the arms 28 and act between the bracket 27 and the arms for normally urging the arms towards the guides 14. The rollers 29 will thus engage the guides irrespective of the 80 width of the guides which varies when the U shaped members are extended.

A means is provided for hoisting the carriage 25, to various elevations relative to the outer U shaped member 13. This means comprises a 85 cable 31, attached upon the top of the carriage 25, and extended over a roller 32 mounted upon the upper end of the outer U shaped member. This cable may be drawn manually or a drum hoist, not shown on the drawing, may be employed. The various U shaped members 13, may be extended relative to each other in that each of the U shaped members has a cable 33 attached upon its lower end at 34 and extended over a roller 35, mounted at the upper end of the inner 90 adjacent U shaped member. These various cables may be drawn by hand to extend the members or some drum hoist, not shown on the drawing, may be provided. The ends of the 95 arms of the U shaped members are bent away 100 from each other, and in these spaces the cables 33 pass.

In Figure 2 a variation of the invention has been disclosed in which the safety elevator is shown mounted upon a truck 36. In other respects it is identical to the form shown in Figure 1.

The operation of the device consists in extending it from its normally closed horizontal position to an inclined position against a building 110

so that in the event of fire or emergency people may be carried down. The various U shaped members may be engaged at different inclinations against the building and be extended to different degrees so that the device can reach any of the floors of a building.

While I have shown and described the preferred embodiment of my invention, it is to be understood that I do not limit myself to the 10 precise construction herein disclosed and the right is reserved to all changes and modifications coming within the scope of the invention as defined in the appended claims.

Having thus described my invention, what I 15 claim as new, and desire to secure by United States Letters Patent is:—

1. A safety elevator, comprising a plurality of substantially U shaped members one set into the other and having a plurality of guides on each 20 of the arms thereof extended inwards and set one in the other, means for holding the U shaped members in various inclined positions, means for extending each succeeding outer U shaped member relative to the adjacent inner one, a carriage disposed between the arms of the U shaped members and having roller structures resting on said guides, and means for hoisting the carriage relative to the U shaped members, said roller structures comprising brackets attached upon 25 the sides of the carriage, arms swivelly connected with said brackets, resilient means urging said arms inwards, and rollers on the ends of said arms.

2. A safety elevator, comprising a plurality of substantially U shaped members one set into the other and having a plurality of guides on each 30 of the arms thereof extended inwards and set one in the other, means for holding the U shaped members in various inclined positions, means for 35 extending each succeeding outer U shaped mem-

ber relative to the adjacent inner one, a carriage disposed between the arms of the U shaped members and having trucks resting on said guides, and means for hoisting the carriage relative to the U shaped members, the outer edges of said 80 U shaped members being spread from each other, and the means for extending the U shaped members relative to each other including cables running within the spaces between said bent edges. 85

3. A safety elevator, comprising a plurality of substantially U-shaped members one set into the other and having a plurality of guides on each of the arms thereof, extended inwards and set one in the other, means for holding the U-shaped members in various inclined positions, means for extending each succeeding outer U-shaped member relative to the adjacent inner one, a carriage disposed between the arms of the U-shaped members and having roller structures resting on said guides, and means for hoisting the carriage relative to the U-shaped members, said roller structures comprising arms swivelly mounted, resilient means urging said arms inwards, and rollers on the ends of said arms. 90 95

4. A safety elevator, comprising a plurality of substantially U-shaped members one set into the other and having a plurality of guides on each of the arms thereof, extended inwards and set one in the other, means for holding the U-shaped members in various inclined positions, 105 means for extending each succeeding outer U-shaped member relative to the adjacent inner one, a carriage disposed between the arms of the U-shaped members and having roller structures resting on said guides, and means for 110 hoisting the carriage relative to the U-shaped members, said roller structures comprising spaced rollers resiliently urged towards each other. 115
